JEROME I. ANSON, OF DAYTON, OHIO, ASSIGNOR TO DELCO PRODUCTS CORPORATION, OF DAYTON, OHIO, A CORPORATION OF DELAWARE

CHARGE FORMING DEVICE

Application filed June 12, 1929. Serial No. 370,191.

This invention relates to charge forming devices for internal combustion engines and most particularly to the type of charge forming device which comprises a plurality of 5 primary carburetors, one for each intake port of the engine, which cooperate respectively with a plurality of secondary mixing chambers located adjacent the engine intake ports, and which receive primary mixture 10 from pipes connected with the primary mixing chamber, while receiving additional air under certain operating conditions through branches of an air manifold having a single air inlet passage controlled by a single main 15 air throttle.

Examples of charge forming devices of this character are shown in the copending application of Fred E. Aseltine and Wilford H. Teeter, Serial No. 221,371, filed September 22, 1927 which matured to Patent 1,819,495 granted Aug. 18, 1931 and Wilford H. Teeter, Serial No. 312,509, filed October 8, 1928, which matured to Patent 1,849,499 granted Feb. 23, 1932 and the present invention 25 constitutes an improvement on the device disclosed in the later filed application.

The device disclosed in the above application of Wilford H. Teeter involves a departure from the construction of earlier devices of this character. This change in construction comprises the provision of separate air inlets for the primary carburetors and secondary mixing chambers, controlled by 30 separate spring closed valves, the purpose of this change in construction being to improve the mixture proportioning under certain operating conditions, particularly during acceleration and on operation at low engine speeds. In the Teeter construction the admission of air to the primary carburetor is entirely automatically controlled being regulated solely by the suction of the engine and the air valve spring itself.

45 The primary purpose of the present invention is to provide means to control the admission of air to the primary mixing chambers, in such a manner that the device is effective to supply a mixture of more nearly ideal proportions, particularly during the

acceleration period and on operation at relatively high engine speeds.

This general purpose is accomplished according to this invention by providing a separate air inlet supplying air to the primary mixing chambers, and a suction operated, spring closed, valve for regulating the flow through such inlet, which is provided with means operated by the throttle for increasing the pressure of said spring on the valve 55 as the throttle opens, after said throttle has made a predetermined amount of movement, said means being constructed so as to have no effect on the spring during the first part of the opening movement of said throttle. 60

Further objects and advantages of the present invention will be apparent from the following description, reference being had to the accompanying drawing, wherein a preferred embodiment of one form of the 70 present invention is clearly shown.

In the drawing:

Fig. 1 is a vertical longitudinal section through a charge forming device embodying the present invention and one of the associated engine intake ports.

Fig. 2 is a fragmentary transverse section on the line 2—2 of Fig. 1.

Fig. 3 is a fragmentary side elevation showing the throttle operating connections.

Fig. 4 is a fragmentary front elevation viewed from the left in Fig. 1.

The device disclosed comprises a main air manifold 10 having three outlet branches, the middle branch 12 being shown herein. Each 85 of these branches communicates with one of the intake ports 14 of a multicylinder engine. These outlet branches are each provided with an attaching flange 16 for securing the manifold to the engine block in the usual manner. Adjacent the inlet of the manifold is provided a flange 18 to which the main carburetor unit is adapted to be attached, as shown in Fig. 1.

The carburetor unit comprises a main housing 20 having an attaching flange 22, adapted to be secured to the flange 18 by screws 24. An air inlet horn 28 is secured in position to register with an opening in the upper wall of the housing 20 in any suitable way. A cast- 95

100

ing 30, having certain dash pot chambers and fuel passages formed therein, is secured by screws to the lower wall of the housing 20 and a sheet metal fuel bowl 32 is held tight against a shoulder 34 on said housing by any suitable means. Fuel is conducted from a main source of supply to the fuel bowl through a conduit, not shown herein, and the flow of fuel to the bowl is controlled by a float 36 operating in the usual manner to maintain a substantially constant level of fuel therein.

Fuel flows from the bowl 32 to a plurality of primary fuel nozzles 38, one of which is located in each of the primary mixing chambers 40, the construction of which is briefly described hereinafter. The fuel conduit between the fuel bowl and the nozzles comprises a vertical fuel passage 42 communicating at its upper end with a horizontal fuel canal 44, which connects with each of the nozzles 38 through orifices 46. Fuel is admitted from the fuel bowl to passage 42 at all speeds through a fixed metering orifice 48 and at high speeds additional fuel is admitted through an orifice 50 controlled by a valve 52 in the manner set forth in the above mentioned applications.

Fuel is lifted from the fuel bowl through the above described fuel passages and nozzles 38 to the mixing chambers 40 by the suction therein. Closing movements of the throttle cause a reduction in mixing chamber suction, which might permit the fuel column to drop sufficiently to cause a temporary fuel starving of the engine unless means were provided to prevent such action. For this purpose a check valve 54 is provided in an enlarged chamber 56 at the junction of channels 42 and 44, and on reduction of mixing chamber 40 suction seats on the bottom of this chamber, preventing downward flow of fuel.

Each primary fuel nozzle is provided with a main fuel outlet 58 in the top of the nozzle and a secondary fuel outlet comprising two orifices 60 and 62 in the vertical wall of the nozzle near the bottom of the mixing chamber. At relatively high speeds the mixing chamber suction is sufficient to lift fuel from the main fuel outlet as well as from the holes 60 and 62. At idling and low speed operation under load, however, the suction is enough to lift fuel only to some point between the top of the nozzle and orifices 60 and 62, fuel then flowing from these orifices only by action of gravity. Each nozzle is provided with a restricted fuel metering orifice 63. The primary mixing chambers 40 comprise the enlarged anterior ends of primary mixture passages 64, which are parallel to each other and close together, as indicated in Fig. 2, and when the carburetor is attached to the manifold, these passages register with conduits which convey the primary mixture to the secondary mixing chambers, as fully disclosed in the copending application referred

to. Each primary mixture passage is provided with a restriction 65 immediately posterior to the enlargements 64, for the purpose of reducing the velocity of flow past the fuel nozzles.

A single throttle valve 66, which extends across all the primary mixture passages, controls the flow therethrough and is provided with grooves 68 which register with said mixture passages. This throttle is operated by means shown in Fig. 4, and is briefly described hereinafter. The middle primary mixture passage connects with a tube 70 fixed in the manifold branch 12, which conveys the primary mixture to the secondary mixing chamber in that manifold branch.

According to the present invention air is admitted to the primary mixing chambers by a primary air passage 72, which supplies air directly to a primary air chamber 74 and is controlled by a valve 76 which will be more fully described hereinafter. The air chamber 74 is formed within the main housing 20 and is large enough to communicate with all the primary mixing chambers. The valve 76 is adjustably secured in any desirable manner, as by means of nuts 78 to the inner end of a valve stem 80, slidably mounted in a short sleeve 82 connected by a spider 84 to a fitting 86 screwed into the housing 20 as indicated in Fig. 1. The valve is normally held in closed position by a spring 88, surrounding the valve stem and receive between a knurled head 90 on the outer end of said stem and a collar 92 slidable on the stem and adapted to be moved by means later described to compress the spring 88 and increase the resistance said spring offers to opening movement of the valve. As the throttle 66 is opened the valve 76 is opened against the pressure of spring 88 to supply air to all the primary mixture passages.

Air is supplied to the secondary mixing chambers through the inlet horn 28 and is controlled by a valve 94, hereinafter designated the main or secondary air valve, which is normally held against a seat 96 by a spring 98 which is stronger than the spring 88. This spring is received between the valve and a flange 100 projecting from a sleeve 102 slidably mounted on a stationary guide sleeve 104, fixed in the housing 20, and serving as a guide for the stem 105 to the upper end of which the valve 94 is secured.

When it is desired to choke the carburetor to start the engine the flange 100 is adapted to be lifted by means not shown herein but fully described in the copending applications referred to, to bring the upper end of the sleeve 102 into engagement with the valve 94 to hold it closed. Sufficient air to carry the starting fuel from the nozzles to the intake ports is admitted by the primary air valve 76.

The main air valve admits air directly to

a main air chamber 106 formed in the main housing above the primary air chamber 74 and separated therefrom by a partition wall 108. Air flows from this chamber to the secondary mixing chambers through a passage 110 which connects with the inlet of the air manifold 10. A manually operable air throttle 112 secured to a shaft 114 rotatably mounted in the housing 20, controls the flow of air through the passage 110, said valve being operated from the primary throttle through the medium of connections which will now be very briefly described. These operating connections are fully described in the earlier copending cases above referred to but it is sufficient for the purposes of the present disclosure to state that the primary throttle is operated by means of an arm 116 secured in any desirable manner to a spindle 118 projecting from one end of the throttle, and adapted to be connected at its free end to some form of connection extending to a point convenient to the operator of the vehicle. The operating arm is connected by means of a lost motion connection, indicated in its entirety by the reference number 120, to an arm 122 secured to one end of the shaft 114. This construction permits a limited movement of the primary throttle independent of the air throttle 112, enabling the primary throttle to be partially opened while the air throttle remains completely closed. The lost motion connection is capable of adjustment and is generally adjusted so that only the primary throttle is opened, while the vehicle on which the carburetor is used is running at speeds below a speed of approximately 15-20 miles per hour on a level. At this speed the throttle 112 begins to open and at all higher speeds the two throttles move simultaneously.

To prevent opening of the valve 94 sufficiently to lean the mixture, and also to prevent fluttering of said valve a dash pot is provided, comprising a piston 124 secured to the lower end of the valve stem 105, slidably received in a cylinder 130 formed in the casting 30 and adapted to be filled with fuel from the fuel bowl 32, a check valve (not shown) being provided in the bottom of the dash pot. This dash pot is of conventional form and the details of construction hereof constitute no part of the present invention.

As previously stated the spring 88 which holds the valve 76 closed is relatively weak by comparison with the spring of the main air valve. This construction is provided to accomplish two results, as fully explained in application Serial No. 312,509. First it opposes relatively little resistance to the opening of valve 76 so that even at low speeds the valve opens to a considerable extent admitting sufficient air to maintain a relatively low suction at the jets so as to form a relatively lean mixture, thus correcting a tendency noticeable in earlier devices of this char-

acter and due to the relatively high suction at the fuel jets as determined by the stronger main air valve spring, to form a mixture which is too rich in the low speed range. Second, by providing a weak spring on the valve 76, the pressure in the primary air chamber 74 is maintained higher than would be possible if the chamber were supplied with air from the main chamber 106 in which the suction is determined by the main air valve 94. Accordingly the difference between the pressure in chamber 74 and that at the posterior ends of the primary mixture conduits is greater and the velocity of flow through such conduits is greater than would be possible if the suction in chamber 74 were determined by the stronger main air valve spring. This construction produces improved acceleration because the time interval necessary for the rich primary mixture to reach the secondary mixing chambers on any opening movement of the throttle is reduced, and more nearly approaches the time required for air to flow from the chamber 106 to said secondary mixing chambers, whereby the increased supply of rich primary mixture and increased quantity of air resulting from the opening of the throttle reach the secondary mixing chambers substantially simultaneously.

The use of the relatively weak spring on the primary air valve to secure the advantages above referred to, results in too low a suction at the fuel jets at higher engine speeds, or during operation under heavy load at low speed with open throttle. This results in the formation of too lean a mixture for satisfactory operation under the conditions referred to. To avoid this difficulty means are provided to increase the pressure of the spring tending to hold the valve closed as the throttle is opened. This means comprises an angular operating arm 140 pivoted on a screw 142 screwed into a lug 144 projecting from the housing 20 and integral therewith. The free end of the arm 140 is bifurcated to form two short arms 146 as shown in Fig. 4. The valve stem 80 is received between the arms 146, which lie between the collar 82 and the spider 84. Pivotedly connected to the arm 140 by a pin 148, positioned at a point intermediate the length of the arm, is a link 150, connected at its other end to a pin 152 projecting from the operating arm 122 of the main air throttle. Obviously as the main air throttle is opened, the link 150 is moved to the left in Fig. 3, increasing the pressure of the spring 88 on the head 90 of the valve stem, thus insuring a higher suction at the fuel jets than would be possible if the effect of the spring were unmodified and also delaying the opening movement of the valve with respect to the throttle.

It will be clear from the foregoing that the means for increasing the resistance of the spring 88 to opening of the valve not only overcomes the tendency to form a too lean

mixture at high speeds but aids the operation during the acceleration period as well. The delay in opening of the valve 76 relative to the throttle results in a further temporary 5 increase in suction at the jets during the acceleration period which will result in a temporary enrichment of the mixture during this period which is necessary to give the desired power for smooth acceleration.

10 Each secondary mixing chamber comprises a Venturi tube 160, positioned in the outlet of each branch of the manifold and surrounding the outlet end of the primary mixture conduit therein. The venturi is provided with an external rib 162, which is clamped between shoulders 164 and 166, on the manifold and the engine block respectively, when the device is assembled. These 15 Venturi tubes increase the velocity of flow past the ends and increase the velocity of flow therethrough for a purpose fully set forth in the earlier application above referred to.

20 While the form of embodiment of the present invention as herein disclosed, constitutes a preferred form, it is to be understood that other forms might be adopted, all coming within the scope of the claims which follow.

25 What is claimed is as follows:

30 1. A charge forming device for internal combustion engines comprising a primary mixing chamber, means for supplying fuel and air thereto, a throttle, a secondary mixing chamber into which the primary mixing chamber delivers and relatively remote from the primary mixing chamber, separate suction operated means for controlling the admission of air to said mixing chambers, said means being responsive to different degrees of suction, and means for variably and automatically regulating the degree of suction necessary to operate the air admission means for the primary mixing chamber, during 35 operation of the engine under varying operating conditions.

40 2. A charge forming device for internal combustion engines comprising a primary mixing chamber, means for supplying fuel and air thereto, a throttle, a secondary mixing chamber into which the primary mixing chamber delivers and relatively remote from the primary mixing chamber, a valve controlling the admission of air to the primary mixing chamber and adapted to admit air thereto at all times when the engine is running, a valve controlling the admission of air to the secondary mixing chamber during only a part of the engine operation, and means for 45 automatically and variably controlling the opening movement of said first mentioned valve during operation of the engine under varying operating conditions.

45 3. A charge forming device for internal combustion engines comprising a primary

mixing chamber, means for supplying fuel and air thereto, a throttle, a secondary mixing chamber into which the primary mixing chamber delivers and relatively remote from the primary mixing chamber, a valve controlling the admission of air to the primary mixing chamber and adapted to admit air thereto at all times when the engine is running, a valve controlling the admission of air to the secondary mixing chamber during only a part of the engine operation, and means operated by the throttle for automatically and variably controlling the opening movement of one of said valves, during operation of the engine under varying operating conditions.

4. A charge forming device for internal combustion engines comprising a primary mixing chamber, means for supplying fuel and air thereto, a secondary mixing chamber into which the primary mixing chamber delivers, spring held primary and secondary valves controlling the admission of air to said mixing chambers respectively, the spring of said primary valve being weaker than that of the secondary valve whereby a low suction is maintained in the primary mixing chamber under certain operating conditions, and means for automatically increasing the pressure of said spring under other operating conditions.

5. A charge forming device for internal combustion engines comprising a primary mixing chamber, means for supplying fuel and air thereto, a secondary mixing chamber into which the primary mixing chamber delivers, a primary throttle controlling the flow from said primary mixing chamber, a secondary throttle regulating the secondary mixing chamber, primary and secondary air valves controlling the admission of air to said mixing chambers, means for resisting the opening of said primary air valve, common operating mechanism for operating both said throttle valves and controlling the effectiveness of said resisting means.

6. A charge forming device for internal combustion engines comprising a primary mixing chamber, means for supplying fuel and air thereto, a secondary mixing chamber into which the primary mixing chamber delivers, a primary throttle controlling the flow from said primary mixing chamber, a secondary throttle regulating the secondary mixing chamber, means for opening the secondary throttle after the primary throttle begins to open, primary and secondary air valves controlling the admission of air to said mixing chambers and means connected to the secondary throttle for controlling the opening of the primary air valve during the opening of said secondary throttle.

7. A charge forming device for internal combustion engines comprising a primary

- mixing chamber, means for supplying fuel and air thereto, a secondary mixing chamber into which the primary mixing chamber delivers, a primary throttle controlling the flow from said primary mixing chamber, a secondary throttle regulating the secondary mixing chamber, primary and secondary air valves controlling the admission of air to said mixing chambers, means operable to resist the opening of the primary air valve, and means operable after a predetermined opening movement of the primary throttle to increase the resistance to opening movement of said primary air valve.
8. A charge forming device for internal combustion engines comprising a primary mixing chamber, means for supplying fuel and air thereto, a secondary mixing chamber into which the primary mixing chamber delivers, primary and secondary throttles controlling the flow from said mixing chambers, an operating arm connected to said secondary throttle, operating means connecting said primary throttle with said arm, spring closed primary and secondary air valves controlling the admission of air to said mixing chambers, an arm engaging the spring of said primary air valve to increase the pressure of said spring on the valve, and a link connecting said arm and the operating arm of the secondary throttle.
9. A charge forming device for multicylinder engines comprising a plurality of secondary mixing chambers, a plurality of primary mixing chambers associated therewith and supplying primary mixture thereto, means supplying fuel to said primary mixing chambers, primary and secondary throttles controlling the flow from said primary and secondary throttles, a single primary air valve for admitting air to all of said primary mixing chambers, a single secondary air valve for admitting air to all of said secondary air chambers and means operated by the secondary throttle for controlling the operations of said primary air valve.
10. A charge forming device for internal combustion engines comprising a primary mixing chamber, means for supplying fuel and air thereto, a secondary mixing chamber into which the primary mixing chamber delivers, a primary throttle controlling the flow from said primary mixing chamber, a secondary throttle regulating the secondary mixing chamber, primary and secondary air valves controlling the admission of air to said mixing chambers, means operable to resist the opening of the primary air valve, and means operable by the secondary throttle after a predetermined movement thereof to increase the resistance of said resisting means.
11. A charge forming device for internal combustion engines comprising a primary mixing chamber, means for supplying fuel and air thereto, a secondary mixing chamber into which the primary mixing chamber delivers, spring held primary and secondary valves controlling the admission of air to said mixing chambers, the spring of said primary valve being weaker than that of the secondary valve whereby a low suction is maintained in the primary mixing chamber under certain operating conditions, and means effective to increase the pressure of the spring on the primary air valve on opening of the throttle.
12. A charge forming device for internal combustion engines comprising a primary mixing chamber, means supplying fuel and air thereto, a throttle, a secondary mixing chamber, a primary mixture conduit adapted to convey primary mixture from the primary chamber to said secondary chamber, a spring held valve controlling admission of air to the primary mixing chamber and adapted to open under relatively low suction, a spring held valve controlling admission of air to the secondary mixing chamber and opening only under relatively high suction, and means for automatically varying the spring pressure on the primary air valve.
13. A charge forming device for internal combustion engines comprising a primary mixing chamber, means supplying fuel and air thereto, a throttle, a secondary mixing chamber, a primary mixture conduit adapted to convey primary mixture from the primary chamber to said secondary chamber, a spring held valve controlling admission of air to the primary mixing chamber and adapted to open under relatively low suction, a spring held valve controlling admission of air to the secondary mixing chamber and opening only under relatively high suction, and means operable during opening movements of the throttle for varying the spring pressure on the primary air valve.
14. A charge forming device for internal combustion engines comprising a primary mixing chamber, means supplying fuel and air thereto, a throttle, a secondary mixing chamber, a primary mixture conduit adapted to convey primary mixture from the primary chamber to said secondary chamber, a spring held valve controlling admission of air to the primary mixing chamber and adapted to open under relatively low suction, a spring held valve controlling admission of air to the secondary mixing chamber and opening only under relatively high suction, and means operable by the throttle for varying the spring pressure on the primary air valve.
15. A charge forming device for internal combustion engines comprising a primary mixing chamber, means for supplying fuel and air thereto, a throttle controlling the flow therefrom, a secondary mixing chamber to which the primary mixing chamber sup-

- plies a primary mixture of fuel and air, a primary air valve admitting air to the primary mixing chamber at all times when the engine is running, a secondary air valve admitting air to the secondary mixing chamber during only a part of the engine operation, and means operated by the throttle for variably controlling the opening movement of the primary air valve during all opening movement of the secondary air valve.
16. A charge forming device for internal combustion engines comprising a primary mixing chamber, means for supplying fuel and air thereto, a throttle controlling the flow therefrom, a secondary mixing chamber to which the primary mixing chamber supplies a primary mixture of fuel and air, a primary air valve admitting air to the primary mixing chamber at all times when the engine is running, a secondary air valve admitting air to the secondary mixing chamber during only a part of the engine operation, means operated by the throttle for operating the secondary air valve, and means connected to the secondary air valve for variably controlling the opening movement of the primary air valve after the secondary air valve begins to open.
17. A charge forming device for internal combustion engines comprising a primary mixing chamber, means for supplying fuel and air thereto, a throttle controlling the flow therefrom, a secondary mixing chamber to which the primary mixing chamber supplies a primary mixture of fuel and air, a spring closed suction operated primary air valve, a suction operated air valve admitting air to the secondary mixing chamber, and means operated by the throttle for increasing the spring pressure on the primary air valve as the throttle is opened.
18. A charge forming device for internal combustion engines comprising a primary mixing chamber, means for supplying fuel and air thereto, a throttle controlling the flow therefrom, a secondary mixing chamber to which the primary mixing chamber supplies a primary mixture of fuel and air, a spring closed suction operated primary air valve, a secondary air valve admitting air to the secondary mixing chamber only, and means operated by the throttle for increasing the spring pressure on the primary air valve only during the opening movement of the secondary air valve.

In testimony whereof I hereto affix my signature.

JEROME I. ANSON.
